UNITED STATES PATENT OFFICE.

EDGAR J. BLOOM, OF TIFFIN, OHIO.

FLUSHING-VALVE.

1,186,000.

Specification of Letters Patent. Patented Apr. 18, 1916.

Application filed April 1, 1909. Serial No. 487,804.

To all whom it may concern:

Be it known that I, EDGAR J. BLOOM, a citizen of the United States, residing at Tiffin, county of Seneca, State of Ohio, have invented a certain new and useful Improvement in Flushing-Valves, and declare the following to be a full, clear, and exact description of the same, such as will enable others skilled in the art to which it pertains to make and use the same, reference being had to the accompanying drawings, which form a part of this specification.

My invention relates to flushing valves, and consists in the improvements herein-
15 after described and pointed out in the claims.

In the accompanying drawings, Figure 1 is a longitudinal central section of a flushing valve embodying my invention. Fig. 2 is a cross section in the plane indicated by the line 2^a—2^a, Fig. 1. Fig. 3 is a perspective view of the conical four-way cock plug removed from the cock chamber. Fig. 4 is a detail view showing the end of the stem of the conical four-way cock plug. Fig. 5 is a detail cross section in the plane indicated by the line 5^b—5^b, Fig. 2, looking from the right of said figure. Fig. 6 is a side elevation of an apparatus with a flushing valve embodying my invention, secured in place. Fig. 7 is a detailed section on the line 7^b—7^b, Fig. 2. Fig. 8 is a section, to a reduced scale, in the plane indicated by the line 8—8, Fig. 1. Fig. 9, is a detail view showing the head of the screw I, the cap J being removed.

2 is a cylinder in which a double piston 10, consisting of two parts P², P² connected by a part P¹ of less diameter than the parts 40 P², P², is adapted to reciprocate. t is an inlet passage adapted to communicate with a source of water supply under pressure, and T is a port opening into the center of the cylinder 2 from the passage t.

45 T¹ is an outlet passage opposite the inlet passage t.

D is a conical four-way cock plug adapted to fit and turn within a conical chamber D¹.

50 L L and M M are grooves cut in the plug D of the conical four-way cock, and B, B are ports cored through the wall of the chamber. The ports B, B are extended in slots N, N.

B¹, B¹ are ports through the wall of the 55 chamber D¹, at ninety degrees from the ports B, B and extended in slots N¹, N¹.

A is a passageway drilled in the wall of the cylinder 2, communicating at one end with the entrance passage t, and at the other end with a port B, opening through the 60 wall of the conical four-way cock chamber D¹.

A³ is a passageway drilled in the wall of the cylinder 2, communicating at one end with the exhaust passage u, and at the other 65 end with a second port B opening through the wall of the conical four-way cock chamber D¹.

A¹, A^{1a} (Fig. 1) are passageways drilled in the wall of the cylinder 2, said passageways extending from the respective ends of said cylinder and open at their inner ends to ports B¹, B¹, respectively opening through the conical four-way cock chamber D¹ at positions ninety degrees from the ports B, 70 B. The ends of the cylinder 2 are thickened to produce broad surfaces for receiving a washer and cap plates C, C. These cap plates are hollowed out, the cavity opening within the cylinder 2, and said cavity is 75 surrounded by a valve seat 3.

a is a passage in the wall of each of the caps C, C, one end of which opens to the cavity in said cap and the other end registers with the end of a passage A¹, A^{1a}. 85

The piston within the cylinder 2 consists of two ends parts P², P², adapted to fit loosely within the bore of the cylinder 2, and a part P¹, smaller in diameter than the parts P², P², joining the last named parts. 90 The part P¹ is formed in cross section, as shown in Fig. 2, so as to present the ratchet-like steps, or projections P, so that a vertical or concave surface is presented to the stream entering the port or passage T, upon one side of a plane in which the axes of the piston 10 and piping T, Q, R, both lie and an inclined surface upon the other side. The steps P are formed spiral, so that one step shall never entirely cover the other, but 95 a concave or vertical surface shall always be presented to the stream of entering water.

4, 4 are disks secured on the ends of the piston P², P² adapted to seat against the valve seat 3, at one end or the other of the cylinder 2, so that when the piston is at the end of its stroke it shall be firmly held there by main water pressure which enters the chamber through by-passes and has moved the piston over to the opposite end, notwithstanding there may be some leakage past the piston heads P², P². 100 110

f is a stem extending from the outer end of the conical four-way cock plug D. The stem *f* is formed into an approximately square cross section for a portion of its length *g*, at the outer end of said stem.

H is a handle adapted to fit upon the squared portion *g* of the stem *f*, to turn the conical four-way cock plug D to the various positions. When the handle H is turned toward one extreme of its angular travel, one of the passages A¹ or A^{1a} is put into communication with the passage A and the source of pressure, while the other passage A^{1a} or A¹ is put into communication with the passage A³ and the discharge passage *u* of the valve. In this position the first named passage conducts water under pressure to one end of the cylinder 2, which forces the piston in said cylinder toward the other end of the same, while the water is exhausted through the passage A³ from said other end of the cylinder 2. When the piston 10 is at the extreme end of its travel, one of the heads P¹, P² is opposite the ports T and T¹, closing the same, except for the leakage past the piston which is made about .004 inch smaller than the bore of the cylinder. When the piston is in transit, a head P² of the piston passes from opposite the ports T and T¹, allowing the water to rush from the port T transversely across the cylinder 2, between the heads P¹, P² of the piston, and out at the exhaust port T¹. The stream of water in passing impinges against the steps P on the intermediate portion P¹ of the piston 10, acting most strongly upon that step which presents a concave or vertical surface to said stream, thus causing the piston 10 to rotate. Thus the piston is continually turned in the cylinder and wears uniformly. Owing to the fact that the piston heads P¹, P² are about four thousandths of an inch smaller than the bore of the cylinder 2, there is always a lubricating film of water between the cylinder walls and said heads.

The speed with which the piston 10, traverses the cylinder 2 depends upon the extent of opening from the passages A, and also upon the pressure of the water in the inlet passage *t*, so that an approximately uniform quantity of water is discharged at each operation without regard to whether there is more or less pressure, because if the pressure is high, the water will be forced through the ports T and T¹ at a greater rate, but at the same time, the water will be forced through the passage A at a proportionately greater rate, so that the time of traverse of the piston will be proportionately shorter.

h is a lug upon the cylinder 2.

*h*² is a sector-like trough, U-shaped in cross-section, formed upon the handle H and embracing the lug *h*.

*h*³, *h*⁴ are set screws at each end of the sector-like trough *h*², which screws strike against the lug *h* to limit the motion of the handle H. In the ordinary operation the handle H is thrown to one or the other extreme of its travel and the extent to which the passage A is opened is regulated by adjusting the set screws *h*³, *h*⁴, and consequently the amount of water passing at each operation is regulated by the adjustment of said screws.

It will be noted that there are slots M in the four-way cock plug (Fig. 3). Said slots are located at a different angular position from that of the slots L, so that when said plug is turned to a position such that the slots L do not communicate with a port in the wall of the four-way cock chamber, then the slots M will form a communication with the extension slots N and N¹ and the piston will be carried to the end of its travel and will not be held in an intermediate position.

The squared portion *g*, of the stem *f* of the conical four-way cock plug D, is slotted, as indicated distinctly in Fig. 4, and has one corner cut away, as also indicated in that figure. The aperture in the handle H has one corner filled in to fit the cut away portion of the squared part *g*, so that said handle can be placed upon the stem in only one position. Said part *g* is bored centrally to receive the conical head of a screw I, the threads of the shank of which engage threads in the lower portion of the bored out part of said stem. The head of the screw I is provided with external screw-threads toward its outer end, and at this part the head is partly flattened or cut away so that it may be engaged by a wrench to manipulate the screw. By forcing the screw I in by means of a wrench engaging its head, the squared part *g* of the stem is expanded to fit accurately the aperture in the handle H, so that there is no lost motion between the handle and stem and the angular position of the handle is accurately fixed relative to the conical four-way cock plug D.

K is a buffer, or button, of rubber or other suitable resilient material, placed upon the head of the screw I.

J is a cap-like nut, the threads of which engage the threads on the heads of the screw I. There is an aperture through the outer end of the nut J and the edges around said aperture are turned inward to form a shoulder engaging a corresponding shoulder on the button K. By screwing down the nut J the button K is firmly fixed in position and a yielding pressure is brought upon the head of the screw I and upon the nut J, which latter also engages the handle H to hold the same firmly in position. The button K protrudes through the outer end of the nut J and by screwing down upon said

nut the button is pressed against the head of the screw I, thus holding it firmly in place. The protruding part of said button forms a buffer against which a cover K^a may strike, 5 as shown in Fig. 6.

G is a gland-nut surrounding the stem f of the conical four-way cock plug D and engaging a screw-threaded boss, which protrudes from the cylinder 2.

10 F is a jam-nut, the threads of which engage with the threads on the boss protruding from the cylinder 2. The nut F is adapted to engage the gland-nut G to fix the same in position. A hard canvas packing 15 E, having a lubrication preparation in same is used under the gland G, and the conical four-way cock plug is held on its seat by the tension of this packing E, caused by the gland-nut G being drawn down on same, 20 and after the proper tension is brought to bear on the conical four-way cock plug D, the lock nut F is used to secure same.

It will be observed that the various passages in the cylinder 2 may be formed by 25 drilling, and coring may be largely avoided. Thus, to form the passage A, a drill may be inserted through the opening t. To form the passage A³, a drill may be inserted through the opening u, and the passageways 30 A¹, A^{1a} may be formed by drilling in from each of the enlarged ends of the cylinder 2. I however form the mouths of the passages, or ports, opening into the four-way cock chamber by coring, and the drilled passages 35 are made to communicate with these short cored passages. Thus the ports are accurately located and it is not necessary to take as much pains in drilling the passages as would otherwise be necessary. The screw 40 holes, through which the screws are placed to secure the ends C in place, are located irregularly, so that said caps can be secured only in one position and so that the ends of the passages a, shall necessarily register 45 with the outer ends of the passages A¹. The short drilled passages have smooth walls and are easily cleaned.

R is a tail piece leading from the exit opening u.

50 Q is a piece of brass tubing, having its upper end notched, and at its lower end fitting into the tail piece R, so that it will easily slide up and down, leaving a space above the tail piece R and outside of said 55 tubing with which the passage A³ communicates. Said space forms the water seal for the passage A³. In addition to the usual function such a seal acts to prevent a noisy discharge.

What I claim is:—

1. In an apparatus of the kind described, 60 the combination of a cylinder having an inlet passage and an exit passage, a piston controlling communication between said passages, an auxiliary valve controlling the 65 movement of said piston, and a passage A³ adapted to deliver water from said auxiliary valve into said exit passage at the side and toward the inner end thereof, said exit passage comprising a tail piece R having 70 its inner end located at a point outside of the outlet from the passage A³ and a tube Q open at its inner end, fitting into said tail piece and extending from the inner end thereof to a point in advance of the outlet 75 from the passage A³, so as to form the inner wall of a chamber surrounding the protruding end of said tube.

2. The combination of a cylinder, a piston 80 therein adapted to be reciprocated by fluid pressure, a cock located on said cylinder, said cylinder being provided with a passage leading to one end thereof, and a passage leading to the other end thereof, said cock having a chamber provided with ports 85 communicating with said passages, a plug fitting and turning in said chamber, said plug being provided with a set of slots adapted to communicate with said ports, in one position of said plug, and a second set of slots 90 offset circumferentially from the first set and adapted to communicate with said ports, at another position of said plug, substantially as and for the purpose described.

3. The combination of a cylinder, a piston 95 therein adapted to be reciprocated by fluid pressure, a cock located on said cylinder, said cylinder being provided with a passage leading to one end thereof, and a passage leading to the other end thereof, said cock 100 having a chamber provided with ports having slots N extending therefrom and communicating with said passages, a plug fitting and turning in said chamber, said plug being provided with a set of slots adapted 105 to communicate with said ports in one position of said plug and a second set of slots offset circumferentially from the first set and adapted to communicate with said ports at another position of said plug, substantially as and for the purpose described.

In testimony whereof, I sign this specification in the presence of two witnesses.

EDGAR J. BLOOM.
